UNITED STATES PATENT OFFICE.

SAMUEL B. LAVICK, OF CHICAGO, ILLINOIS.

DESIGN FOR A COMBINED DISPLAY STAND AND CASE.

Application filed May 23, 1927. Serial No. 22,134. Term of patent 7 years.

To all whom it may concern:

Be it known that I, SAMUEL B. LAVICK, a citizen of the United States, residing at Chicago, in the county of Cook and State of Illinois, have invented a new, original and ornamental Design for a Combined Display Stand and Case, of which the following is a specification, reference being had to the accompanying drawing, forming part thereof.

Fig. 1 is a rear perspective view of my design for a combined display stand and case; and

Fig. 2 is a front perspective view thereof.

I claim:—

The ornamental design for a combined display stand and case, as shown.

SAMUEL B. LAVICK.
